UNITED STATES PATENT OFFICE.

JACOB N. BARR, OF MILWAUKEE, WISCONSIN.

DESIGN FOR A LOCOMOTIVE-HEADLIGHT.

SPECIFICATION forming part of Design No. 30,146, dated February 7, 1899.

Application filed January 4, 1899. Serial No. 701,162. Term of patent 14 years.

To all whom it may concern:

Be it known that I, JACOB N. BARR, a citizen of the United States, residing at West Milwaukee, in the county of Milwaukee and State of Wisconsin, have invented and produced a new and original Design for Locomotive-Headlights, of which the following is a specification, reference being had to the accompanying drawings, forming a part thereof.

10 Figure 1 is a front view of a locomotive-headlight made in accordance with my invention. Fig. 2 is a side elevation of the headlight. Fig. 3 is a rear elevation thereof. Fig. 4 is a plan view thereof.

15 Like letters indicate like parts throughout the different views.

As shown in the drawings, the leading or material feature of my design consists in a headlight formed with a vertically-disposed cylindric portion *a*, a dome portion *b*, surmounting the cylindric portion, and a horizontally-disposed reflector portion *e*, projecting forward from the casing *a*. The reflector-casing projects a short distance beyond the cylindric portion *a*, the projecting portion of the reflector-casing being cylindric in form, its diameter approximating the height and diameter of the casing *a*. The outwardly-projecting end of the reflector-casing is covered 25 with a sheet of glass *e*. An outwardly-flaring flange portion *f* forms a continuation of the cylindric portion *a*, the bottom of the flange portion curving downwardly at the sides and up-

wardly at the front and rear. The chimney-cap *h* is dome-shaped. The chimney-neck 35 *h'* curves inwardly and unites the cap with the dome *b*. The outwardly-curved surface of the dome *b* forms a continuation of the inwardly-curved surface of the neck *h'*, while the exterior surface of the cylindric portion 40 *a* forms a continuation of the curved surface of the dome *b*, the surface of the flaring flange being also a continuation of the surface upon the cylindric portion *a*.

The headlight made in accordance with my 45 design conforms in general external appearance to the sand-box and steam-dome now largely used upon locomotives, these three instrumentalities harmonizing in general appearance. The appearance presented by the 50 locomotive equipped with the sand-box, steam-dome, and locomotive-headlight, all having the same general appearance, is a novel and very pleasing one.

Having described my invention, what I 55 claim as new, and desire to secure by Letters Patent, is—

The design for a locomotive-headlight substantially as herein shown and described.

In witness whereof I hereunto subscribe my 60 name this 30th day of December, A. D. 1898.

JACOB N. BARR.
